DISPENSER FOR PRESSURE SENSITIVE TAPE

Theodore H. Krueger, Stratford, Conn., assignor to Better Packages Incorporated, a corporation of New York

Application January 7, 1953, Serial No. 330,087

3 Claims. (Cl. 242—55.5)

This invention relates to means for dispensing tape or the like in strip form from rolls in which means are provided for slitting the tape into two or more narrow strips as it is dispensed.

The invention finds particular utility in connection with dispensers for dispensing pressure sensitive gummed tape. Rolls of tape during storage sometimes become deformed by the progressive lateral displacement of the layers of tape so that the roll assumes a cone-shape. This is known as "coning" and is an extremely common occurrence in the case of rolls of pressure sensitive adhesive tape. In such rolls, particularly in the larger diameters, coning is the rule rather than the exception, because during storage the tape gradually contracts so that the pressure between successive layers is increased. Also the pressure sensitive adhesive coating is in a permanently plastic condition and will flow under the influence of the increased pressure due to shrinkage. One layer will therefore become displaced slightly with respect to the layer under it, and the roll will therefore assume a marked cone formation. This presents serious difficulties when it is attempted to dispense tape from such a deformed roll, and simultaneously slit the tape into two or more narrow strips. If the roll is mounted so as to rotate about a fixed axial position, and the slitter or slitters are also mounted in fixed positions it will be seen that the position of the slitter or slitters with respect to the edges of the tape will change, depending upon the alignment of the part of the tape passing over the slitter. If the roll is aligned so that the slitter is central with respect to the strip of tape, for example where the tape leaves the outside of a coned roll, it will be seen that this position of the slitter will be far from the center of the tape after the roll is nearly used up. If a plurality of slitter knives are used, so as to cut very narrow tape strips one of the slitter knives might even escape the edge of the tape altogether.

The primary object of the present invention is to provide means for overcoming this defect and to properly compensate for the cone-shape of the roll so as to maintain the correct relationship between the slitter knife or knives and the tape being slit thereby. This is accomplished in the form of the invention disclosed by providing guiding means engaging the peripheral portion of the roll which maintains such engagement as the roll decreases in diameter irrespective of the coning of the roll. The roll is thus maintained in such a position that the strip of tape withdrawn therefrom always passes over the slitter knife or knives in predetermined relationship to such knives.

Other objects and advantages of the invention will appear in the course of the following description of one preferred embodiment thereof.

In the accompanying drawings:

Figure 1 is a side elevation of one form of the invention, parts being broken away.

Figure 2 is a horizontal section on line 2—2 of Fig.

2

1, showing the position of the roll at a time near the start of dispensing tape therefrom.

Figure 3 is a section similar to Fig. 2, showing the position of the roll when the roll is nearly used up.

Figure 4 is a fragmentary section on line 4—4 of Fig. 2, showing the mounting of the slitter knives.

Figure 5 is a section of the guide roller on line 5—5 of Fig. 1.

Referring to the drawings in detail, the invention is illustrated in connection with a so-called "open face" type of dispenser; although obviously it may be used with any type of dispenser.

The dispenser shown comprises a base 10 having a vertical supporting wall 12 mounted thereon. Mounted on a hinge pin 14 carried by the wall near the top thereof is a pendulum link 16 having a bearing stud or spindle 18 at the lower end thereof, on which is rotatably mounted a roll carrying spool 20. This may be of any suitable form adapted to support the core 22 of a roll of tape 24. In the form of the invention shown the spool is illustrated as of square shape and comprises a plate with two bent up portions 26, the edges of which form ribs over which the core 22 is slipped. The core should engage the ribs or corners of the plates firmly, but not so tightly that shifting of the core parallel with the axis of rotation is difficult. Obviously any other suitable form of spool might be utilized, the spool being itself mounted for axial movement on its stud or spindle if desired.

Fixed to the wall 12 adjacent to the roll of tape is a stud 28 having a guide roller 30 mounted thereon for free rotation. The guide roller 30 has shallow end flanges 32 and 34 adapted to engage the outer margins of the sides of the roll of tape 24. The roller 30 is preferably made in two longitudinally adjustable parts, as shown for example in Fig. 5, so that the distance between the flanges 32 and 34 may be adjusted to conform to the width of the roll of tape being dispensed. As shown in Fig. 5 the flange 32 includes a roll part 36 from which projects a neck 38 of reduced diameter. Flange 34 forms part of a roll part 40 mounted on the neck 38 and held in adjusted position thereon by a set screw 42. The mounting of the tape spool on the pendulum link 16 allows the roll of tape to hang so that its periphery is in contact with the guide roller 30, and embraced between the flanges of the latter. This relationship is maintained as the roll decreases in size, owing to the action of gravity in swinging the pendulum link about its support 14.

The tape is drawn from the roll either manually or preferably by means of a suitable tape feeding element. In the construction illustrated a feed wheel 44 is provided which is mounted for rotation on a stud 46 projecting from the wall 12 and is formed with spaced adhesion elements 48. This feed wheel is rotated by means of a ratchet lever 50 and a suitable cutter 52 may be provided if desired. The particular feed construction illustrated is similar to that disclosed in patent to Hillmer No. 2,509,641, but obviously other feed means may be used. The tape is pulled from the roller under considerable tension, and without over-running, being maintained taut at all times.

Slitter means are provided between the supply roll and the feed wheel. In the construction shown the slitter means comprises a plurality of slitter elements 54 mounted on a thumb screw 56 screwing into a stud 58. Each of the slitter elements shown comprises a pair of holder plates 60 and 62 between which are clamped a blade 64 which may be in the form of a conventional razor blade. The plate 62 is shown as provided around three sides with flanges 66. A single slitting knife may be provided, or a series of knives may be used, for example three, one or more of which may be adjusted to an inoperative

position by loosening and then tightening the thumb screw (Fig. 4). Spacing rings or washers may be placed on the thumb screw 56 between the blade holders to space the blades as desired. The corners of the slitter knives preferably engage the tape where it passes over a slotted guide roller 68.

In the operation of the device, when a new roll of tape is to be inserted in the machine, it is slipped over the spool 26 to such a position as will enable the edge of the roll to be received between the flanges on the guide roller 30. The position of the latter is definite with relation to the position of the slitter and feed means, and therefore determines the path of feed of the tape so that the tape is slit on the proper line or lines. If the roll of tape is coned, as shown in Fig. 2, it will be observed that the core of the tape roll 22 is displaced on the spool from the position which it would occupy in true alignment with the roller 30 if the tape roll were flat. This, however, does not prevent the tape, which is fed from the outside of the roll between the flanges of the guide roller, from following the proper path with respect to the slitter knives. As the roll is progressively unwound, its edge portions will still be guided between the flanges on the guide roller, and the unwound portion of the roll will be caused to slide gradually axially of the spool, as indicated in Fig. 3. It is possible to move the roll in this way, as it is a fairly firm structure.

The tape web, however, after stripping from the roll is a fragile web which could not be guided and forced without danger of injury into a predetermined path by rollers or guides which engaged only the thin layer of tape and not the firm edges of the roll itself.

While one preferred embodiment of the invention has been illustrated and described in detail, it is to be understood that changes may be made therein and the invention embodied in other structures. It is not, therefore, the intention to limit the patent to the specific constructions illustrated, but to cover the invention broadly in whatever form its principle may be utilized.

I claim:

1. In a tape dispenser for tightly wound rolls of pressure sensitive adhesive tape in which the rolls are subject to "coning" and in which substantial force is required to separate the outer end of tape from the underlying convolution of the roll as the tape is dispensed, in combination, a frame member, a link pivoted on the frame member, a spool for a roll of tape rotatably mounted on the free end of said link at a point below the pivotal support of the link having a core engaging surface wider than the width of the tape roll and slidably engageable therewith to provide freedom for axial movement of the core portion of the roll of tape, an axially immovable guide roller mounted for rotation about an axis parallel with and at one side of the axis about which a roll of tape carried by said spool will rotate, said guide roller having shallow flanges adapted to closely engage the sides of a roll of tape mounted on said spool near the periphery of said roll only; said link permitting gravity impelled movement of the periphery of the roll toward the guide roller so that it will maintain guiding contact with the inner flange faces of the guide roller and with the periphery of the roller between flanges as the tape is unwound and the roll decreases in size, and feed means for withdrawing tape from the roll and delivering it to a dispensing point, while maintaining the tape taut between the roll and the feed means.

2. In a dispenser for tightly wound rolls of pressure sensitive adhesive tape in which the rolls are subject to "coning" and in which substantial force is required to separate the outer end of tape from the underlying convolution of the roll as the tape is dispensed, in combination, a supporting spool for a roll of tape, said spool being constructed and arranged to provide for rotation of the roll of tape about the axis of the spool and having surface portions of greater axial extent than the tape roll, slidably engageable by the tape roll to provide freedom for movement of the core portion of the roll of tape in an axial direction with respect to the spool axis, a flanged guide roller mounted adjacent to the periphery of the roll of tape and having shallow flanges closely engaging the sides of the roll adjacent to the periphery thereof only, the guide roller being held fixedly against axial movement so that the core of the roll of tape is compelled by the roller to shift axially according to the measure of axial displacement of the periphery of the roll relative to the core of the roll, means for mounting the roll supporting spool and the guide roller for relative movement toward and from one another so as to permit the periphery of the roll of tape to maintain guided contact with the guide roller flanges and periphery as the tape is pulled from the roll, and feed means for guiding the tape to a dispensing point as it is withdrawn from the roll and maintaining the tape taut between the roll and the feed means.
3. In a dispenser for tightly wound rolls of pressure sensitive adhesive tape in which the rolls are subject to "coning" and in which a straight pull involving substantial force is required to separate the tape from the underlying convolution of the roll as the tape is dispensed, and in which bodily fixed means are provided for slitting tape longitudinally as it is dispensed, in combination, a supporting spool for a roll of tape, said spool being constructed and arranged to provide for rotation of the roll of tape about the axis of the spool and having surface portions of greater axial extent than the tape roll slidably engaged with the roll to provide for movement of the roll of tape in an axial direction with respect to the spool axis, a flanged guide roller mounted adjacent to the periphery of the roll of tape and having shallow flanges adjustable toward and from each other in accordance with the width of the tape to be dispensed, said flanges closely engaging the sides of the roll adjacent to the periphery thereof only, means mounting the roll supporting spool and guide roller for relative movement toward one another so as to permit the periphery of the roll of tape to maintain guided contact with the guide roller flanges and periphery as the tape is pulled from the roll, and feed means for guiding the tape to a dispensing point as it is withdrawn from the roll and maintaining the tape taut between the roll and the feed means.
